UNITED STATES PATENT OFFICE.

WALTER O. SNELLING AND GUY A. RUPP, OF ALLENTOWN, PENNSYLVANIA, AS
SIGNORS TO TROJAN POWDER COMPANY, OF NEW YORK, N. Y., A CORPORATION OF
NEW YORK.

METHOD OF AND APPARATUS FOR TRANSPORTING PULVERULENT MATERIALS.

Application filed November 13, 1925. Serial No. 68,841.

This invention relates to the art of handling and transporting pulverulent materials, and it is particularly applicable to materials which are inflammable or explosive in character when dry. Nitrostarch may be taken as an example of such a material. By reason of their explosive character, a considerable risk is involved in shipping such materials in the dry state by railroad or otherwise; and furthermore the transportation charges are excessive by reason of the danger involved. In accordance with our invention, such materials can be conveniently shipped in a wet condition, thus eliminating all danger and enabling the shipper to have the advantage of a low freight rate. We furthermore avoid the use of expensive special containers and the like which have heretofore been considered necessary.

One of the principal objects of the invention therefore is to provide a method of handling pulverulent material whereby for purposes of transportation it may be conveniently supplied to and removed from a container in wet or moist condition.

Another object of the invention is to provide an improved apparatus for the transporting of material in accordance with our improved method.

Further objects of the invention will be apparent from the following specification and claims.

In the accompanying drawings, we have shown several types of apparatus embodying the mechanical features of our invention, and we have illustrated diagrammatically the manner in which the method may be carried on. However, we desire it to be understood that the drawings are for illustrative purposes only and are not to be construed as defining or limiting the scope of the invention, the claims forming a part of this specification being relied upon for that purpose.

Of the drawings:

Figure 1 is a vertical longitudinal sectional view of a tank car embodying the mechanical features of our invention;

Fig. 2 is a transverse vertical sectional view showing an alternate form of tank car embodying the mechanical features of the invention;

Fig. 3 is a view similar to Fig. 2 but showing another alternate embodiment of the mechanical features of the invention;

Fig. 4 is a fragmentary side view of the construction shown in Fig. 3, and

Figs. 5 to 10 are diagrammatic views illustrating the manner of practicing our improved method.

Referring to the drawings, 1 represents a tank adapted to contain the material to be transported, this tank being provided with one or more openings 2, 2, through which material can be supplied to or removed from the tank. Suitable supporting means is provided for the tank whereby the tank may be readily transported, and we have indicated a framework 3 and wheels 4, 4, constituting parts of a railway car. The framework and wheels are indicated diagrammatically, as they do not of themselves constitute any part of the invention. They are or may be of any usual or preferred construction. It will be understood that while we have shown a railway car, the invention is not necessarily so limited, but is applicable to other systems of transportation.

The tank is provided with agitating means located therein and adapted to be operated from the exterior thereof. For a reason which will presently be made clear, we locate the agitating means at a considerable distance above the bottom of the tank.

We do not necessarily limit ourselves to any particular type of agitating means, and two distinct types are shown in the drawings. In Fig. 1 we have shown agitating blades 5, 5, which are mounted at the lower ends of vertical shafts 6, 6. These shafts are carried by bearings 7, 7, secured to the top of the tank, and suitable means is provided for rotating all of the shafts and blades simultaneously. As shown there is a horizontal drive shaft 8 adapted to be rotated by suitable means such as a belt pulley 9. Bevel gearing 10, 10, serves to connect the drive shaft 8 with the several vertical shafts 6, 6. The shaft 8 is carried by bearing brackets 11, 11, preferably formed integrally with the bearings 7, 7. We do not limit ourselves to any definite number of agitating units, but when vertical units are used as shown in Fig.

1, we prefer to provide several of them so that agitation may be effected throughout the entire length of the tank.

For a purpose which will be hereinafter fully specified, we prefer to provide means whereby the tank may be vibrated. We do not limit ourselves to any one type of vibrating means nor to any one location for the vibrating means. However, for purposes of illustration we have shown means whereby the track 12 on which the car rests may be bodily vibrated, thus indirectly causing the vibration of the car structure and of the tank. As shown, there are two pairs of hammers 13, 13, which are vertically movable and which are adapted to impinge against the bottom of the track rails. Associated with the hammers of the respective pairs are cams 14, 14, mounted on transverse shafts 15, 15, which are rotatable by any suitable means (not shown). It will be seen that by rotating the shafts 15, 15, the cams 14, 14, will be caused to reciprocate the hammers 13, 13. The hammers will strike against the track rails and vertically vibrate them, and the vibrations of the rails will be transmitted to the car structure and to the tank.

The construction shown in Fig. 2 is or may be substantially the same as that shown in Fig. 1 except that agitating blades 16, 16, are provided which are rotatable about horizontal axes instead of vertical axes. As indicated, there are two shafts 17, 17, extending longitudinally of the interior of the tank, the shafts being supported by means of bearing brackets 18, 18. The shafts 17, 17, extend through one end of the tank where they are provided with suitable driving devices, as for instance belt pulleys 19, 19, shown by dotted lines in Fig. 2.

It may be desirable, as shown in Fig. 2, to provide a second set of agitating means located close to the bottom of the tank. For this purpose, we have shown two pipes 20, 20, extending longitudinally of the tank and provided with a large number of longitudinally distributed apertures 21 through which either compressed air or a suitable liquid may be discharged into the tank to assist in causing agitation.

The construction shown in Figs. 3 and 4 differs from that shown in Fig. 2 in that the upper agitating means consists of pipes 22, 22, instead of mechanical agitating devices. These pipes 22, 22, are provided with longitudinally distributed apertures 23 through which air or liquid under pressure may be delivered to the tank to effect agitation. As shown in Fig. 4, valves 24 and 60 couplings 25 may be provided for the pipes 20, and valves 26 and couplings 27 may be provided for the pipes 22.

The practice of our improved method and the use of our improved apparatus will be more fully understood by reference to the

diagrammatic Figures 5 to 10. Instead of introducing the pulverulent material into the tank in a dry condition, it is introduced in the form of a paste or slurry. In some cases, the slurry may exist as an incident to the manufacture or prior handling of the material, and in such a case the slurry can be allowed to flow directly into the tank. In other cases, however, when the material exists in a dry condition, a slurry must be formed by mixing the material with water or other suitable fluid, as for instance by means of a mixer 28 indicated in Fig. 5.

When the tank has been filled, the slurry is allowed to stand so as to permit the material therein to settle to the lower part of the tank, leaving a body of supernatant liquid in the upper part of the tank. Fig. 6 shows the pulverulent material separated from the liquid as described. This settling operation can be allowed to take place naturally, but in many cases it will be desirable to accelerate it by vibrating the tank, and thus vibrating the contents thereof. It is a well known physical principle that the settling of pulverulent material from a liquid can be accelerated and expedited by vibrating or jarring. With the apparatus as illustrated, this vibrating or jarring is effected by means of the hammers 13 engaging the track in the manner already described. It is to be understood that in effecting the vibrating, use is made of a rapid succession of sharp quick blows which effect rapid vibration, which is to be distinguished from agitation which would have the reverse of the desired result.

The material which settles to the lower part of the tank may be in the form of a very thick paste, or it may be in the form of a relatively solid cake. It will be obvious that the character of the settled material will depend upon the chemical and physical characteristics thereof. In the case of nitrostarch, particularly when mechanical vibration is utilized, a cake of high density is obtained.

As soon as the settling operation is complete, the supernatant liquid is removed from the tank so as to reduce the weight thereof, and thus reduce the labor, power and expense which would otherwise be involved in transportation. For removing this liquid, a valve may be provided in the tank, but we prefer to remove the liquid through one of the openings 2. For this purpose, we have shown a suction hose 29 connected with a centrifugal suction pump 30.

In many cases, it is preferable to utilize the liquid discharged from the pump 30 for the purpose of forming a slurry with another batch of material to be delivered to another tank. It will be understood that the settling operation is never entirely complete and that some of the material will

remain in suspension in the liquid. By using this same liquid for subsequent batches of material, it will be obvious that all waste can be avoided.

5 As soon as the supernatant liquid has been removed, the tank is transported in the usual way to the point where the material is to be unloaded.

The first step in preparation for unloading is to introduce a body of liquid into the tank, as for instance through a hose 32 shown in Fig. 8.

As soon as the tank has been filled with the liquid, agitation is started to break up the 15 paste or cake at the lower part of the tank so as to form a second fluid slurry. If mechanical agitators of the type shown in Figs. 1 and 2 are provided, power is supplied to operate them, and they are operated until 20 such time as all the material is in suspension. If an agitating means of the type shown in Fig. 4 is provided, fluid may be forced into the tank through one pipe and withdrawn through the other, thus causing a vigorous 25 circulation until the suspension of the material is complete; or the pipes 22, 22 may be connected with a source of compressed air which is allowed to flow through the pipes until the desired result is obtained. By reason 30 of the fact that the material may form a very dense cake, it is usually necessary to locate the main agitating means above the lower part of the tank so as to be above the top of the cake of material. If the agitating 35 means were lower down so as to become embedded in the cake, it would not be possible to start the operation thereof.

In many cases, it is desirable to use a supplemental agitating means in the form of 40 pipes for delivering compressed air, these supplemental agitating means being located near the bottom of the tank for the purpose of completing the mixing of the material with the liquid after the cake has been 45 broken up by the main agitating devices. These supplemental agitating devices also serve to prevent any resettling of the material after the second slurry has been formed.

When the second slurry has been formed, 50 it can be removed from the tank in any desired way. The tank may be provided with a valved opening through which the slurry can flow by gravity, but we prefer to remove it through one of the openings 2. For this 55 purpose, we have shown a hose 33 which is connected with a centrifugal suction pump 34.

What we claim is:

1. The herein-described method of handling and transporting pulverulent material, which consists in supplying the material in the form of a slurry into a tank, permitting the material in the slurry to settle, vibrating the tank to expedite the settling of the ma-

terial, removing the supernatant liquid from the settled material, transporting the tank with the material therein, supplying liquid to the tank to form a second slurry therein, and causing the second slurry to flow out of the tank.

2. The herein-described method of handling and transporting pulverulent material, which consists in supplying the material in the form of a slurry into a tank, permitting the material in the slurry to settle, vibrating the tank to expedite the settling of the material, removing the supernatant liquid from the settled material, transporting the tank with the material therein, supplying liquid to the tank, agitating the liquid and the material to form a second slurry therein, and causing the second slurry to flow out of the tank.

3. The herein-described method of handling and transporting successive batches of pulverulent material, which consists in mixing liquid with the material of each batch to form a slurry, causing the slurry to flow into a tank, permitting the material in the slurry to settle, removing the supernatant liquid from the settled material, returning the liquid thus removed and mixing it with the material of another batch, transporting the tank with the material therein, supplying liquid to the tank to form a second slurry therein, and causing the second slurry to flow out of the tank.

4. An apparatus for transporting pulverulent material comprising a tank having an opening at the top, supporting means in fixed relation to the tank whereby the tank may be readily transported, agitating means comprising power-driven elements located in the tank at a point well above the bottom thereof, and agitating means comprising perforated pipes for admitting fluid under pressure located below the agitating means first mentioned and at a point close to the bottom of the tank.

5. An apparatus for transporting pulverulent material, comprising a tank having an opening at the top, supporting means in fixed relation to the tank whereby the tank may be readily transported, and two sets of agitating means located in the tank for agitating material therein, one of the said sets being mounted well above the bottom of the tank and the other of the said sets comprising perforated pipes located below the first set and close to the bottom for admitting fluid under pressure.

6. An apparatus for transporting pulverulent material, comprising a tank having an opening at the top, supporting means in fixed relation to the tank whereby the tank may be readily transported, means for vibrating the tank to cause pulverulent material therein to settle out of a slurry, and

means located in the tank and separated from the bottom thereof for agitating material therein.

7. An apparatus for transporting pulverulent material, comprising a tank having an opening at the top, supporting means including track wheels in fixed relation to the tank, a track with which the wheels engage to sup-

port the tank, means for vibrating the track and thereby vibrating the tank to cause pulverulent material therein to settle out of a slurry, and means located in the tank and separated from the bottom thereof for agitating material therein. 10
